TOOTHBRUSH

Natal Frolio, Rahway, N. J.

Application March 15, 1933. Serial No. 660,923

2 Claims. (Cl. 15—167)

This invention relates to an improved tooth-brush which in general appearance and construction resembles an ordinary or conventional type brush but which possesses noteworthy structural distinctions and refinements permitting it to function in a more satisfactory and dependable manner.

The principal structural distinction is predicated on the adoption and special adaptation of a bristle head made up of adjustable companion sections joined together and designed in such a manner as to permit it to be used to clean the outer or exposed surfaces of the teeth in the regular way while at the same time permitting satisfactory access to be had for cleaning the inner surfaces of the teeth in a much more practical and effective manner than is capable of accomplishment with present-day marketed forms of brushes.

So far as I have been able to ascertain from limited research work, it is new and novel in this particular line of endeavor to provide a tooth-brush whose head is divided into complementary hingedly connected sections with the inner section formed integral with the handle and the outer section hinged to said inner section, together with means for normally securing the two sections in longitudinal alinement for exterior work and allowing the outer swingable section to assume an angular position with respect to the other section for dependable interior work.

In perfecting a suitable structure for accomplishing these results, I have evolved and produced an arrangement which is characterized by simplicity and economy, appropriateness in shape and proportion, one which is efficient in performance, and otherwise fulfilling the requirements of the invention to the extent that it may be properly acclaimed a mechanical achievement in this particular line of endeavor.

Other features and advantages will become more readily apparent from the following description and drawings. In the accompanying illustrative drawings, wherein like numerals are employed to designate like parts throughout the same:

Figure 1 is a top plan view of a toothbrush constructed in accordance with the principles of the present inventive conception showing the brush section in normal longitudinal alinement.

Figure 2 is a view in section and elevation, the section being taken on the plane of the line 2—2 of Figure 1.

Figure 3 is a view similar to Figure 1 showing the remaining clip or latch released and the

swingable section swung to its extreme open position in which position it is usable for inner cleansing work.

Figure 4 is a horizontal sectional view through the assembly shown in Figures 1 and 2.

Figure 5 is a cross section taken approximately on the plane of the line 5—5 of Figure 2, looking in the direction of the arrows.

Figure 6 is a perspective view of the slideable retaining clip or latch.

Figure 7 is a transverse section taken on the plane of the line 7—7 of Figure 1.

Figure 8 is a detail perspective view of one of the leaves of the hinge.

Referring now to the illustrative drawings, wherein the preferred embodiment of the invention is disclosed, and differentiating the parts by reference numerals, it will be observed that the handle 9 is of ordinary configuration and proportion and that the head 10 possesses conventional configuration and shape but is modified by the presence thereon of the distinguishing features of this invention.

The head 10 may be said to comprise an inner rigid or relatively stationary section 11 and an outer relatively movable or swingable section 12, these being connected together by a hinge 13. The hinge comprises a pair of complementary suitably designed and embellished leaves 14 and 15 joined by a conventional pin and knuckle joint 16. The hinge, as a unit, is seated in an appropriate depression formed in the back of the brush sections and the leaves are flush with the surface of the brush back. This avoids obstructions and permits the device to be reciprocated and oscillated in the mouth without subjecting the user to injury.

The hinge joint is of such construction that it limits the swinging movement of the section 12 to the extreme open position illustrated in Figure 3. In other words, this swingable section has a movement of approximately sixty degrees. When the brush sections break joint in this manner it is ready for use on the interior of the mouth. The brush bristles are merely designated by the numerals 17.

It is of course necessary to provide means to permit the brush sections 11 and 12 to be retained in longitudinal alinement or to allow the sections to assume the angular relationship illustrated in Figure 3. In accomplishing this, the section 11 is provided with spaced parallel bores 18 which register with sockets 19 formed in the sections 12. These bores and sockets

serve to accommodate the slidable U-shaped retaining clip or latch 20 (see Figure 6).

As shown in the last-named figure, this latch is made from wire and includes duplicate arms 21 whose bight or connecting portion 22 are offset slightly as indicated at 23, this offset end portion being extended up through elongated clearance slots 24 as shown in Figure 1. The numeral 25 merely designates a finger grip or knob carried by the portion 22 to permit the latch to be slid back and forth.

When slid outwardly, as shown in Figure 1, the extremities of the arms 21 extend into the sockets 19 and lock the two brush sections 11 and 12 together in the rigid state shown in Figure 2. When the latch is retracted or slid from left to right as shown in Figure 3, and as permitted by the slots 24, the arms are withdrawn from the sockets 19 allowing the section or unit 12 to have freedom of swinging motion so that it can assume the desired angular position with respect to the section 11. Thus, the sections when in the position shown in Figures 1 and 2, are suitable for exterior cleaning work, while in the position shown in Figure 3 are satisfactory for interior cleaning work.

A careful consideration of the foregoing description in conjunction with the illustrative drawings will enable the reader to obtain a clear understanding of the purpose, features and advantages, the explicit construction, and the invention as hereinafter claimed.

It is to be understood that minor changes in shape, size, relative proportions, and materials

may be resorted to in practice without departing from the spirit of the invention or the scope of the invention as now claimed.

I claim:

1. A toothbrush comprising a handle of conventional form having a bristle-equipped brush head at one end, said head being of conventional configuration and design and made up of an inner rigid section and an outer swingable section, hinge means connecting the two sections together, the inner sections being formed with spaced parallel passages and the swingable section with aligned sockets, a U-shaped slidable retaining clip having its arm portions extending through said passages into said sockets to connect the two sections together in alinement, the inner section being slotted, the adjacent end portion of the clip being offset and extended through said slots and provided with a finger operating member.

2. A toothbrush comprising a handle of conventional form having a bristle equipped brush head at one end, said head being of conventional configuration and designed and made up of an inner rigid section and an outer swingable section, hinge means connecting the two sections together, the inner section being formed with spaced parallel passages and the swingable sections with aligned sockets, a U-shaped slidable retaining clip having its arm portions extending through said passages into said sockets to connect the two sections together in alinement.

NATAL FROLIO.
